Helena A. Wild, New York, N. Y.

Application May 17, 1946, Serial No. 129,769

Term of patent 7 years

(Cl. D44—29)

To all whom it may concern:

Be it known that I, Helena A. Wild, a citizen of the United States, residing at New York, in the county of New York and State of New York, have invented a new, original, and ornamental Design for a Pot Holder Rack, of which the following is a specification, reference being had to the accompanying drawing, forming a part thereof.

In the drawing:

Fig. 1 is a front perspective view of a pot holder rack showing my new design;

Fig. 2 is a top plan view; and

Fig. 3 is a side elevational view of the same.

I claim:

The ornamental design for a pot holder rack, as shown.

HELENA A. WILD.
